UNITED STATES PATENT OFFICE.

ERNEST L. PATTEN, OF MALDEN, MASSACHUSETTS, ASSIGNOR TO WELLMAN COMPANY, OF MEDFORD, MASSACHUSETTS, A CORPORATION OF MAINE.

MACHINE FOR CUTTING FORMS.

1,144,429.

Specification of Letters Patent. Patented June 29, 1915.

Application filed June 15, 1914. Serial No. 845,144.

To all whom it may concern:

Be it known that I ERNEST L. PATTEN, of Malden, in the county of Middlesex and State of Massachusetts, have invented a new and useful Machine for Cutting Forms, of which the following is a specification.

My invention relates to machines for cutting forms and I have illustrated it as applied to a machine of the kind disclosed in 10 U. S. Letters Patent No. 647,888 dated April 17, 1900.

In using machines of this class it sometimes happens that an abrupt change of direction is to be made at one or more points 15 of the travel of the leader. At such times lost motion or the shaking of the machine or other causes may give slight, but undesirable, movement of the leader with consequent defective cutting of the material.

20 The main object of my invention is to provide means for holding the leader immovable during a part of the travel of the knife in a form cutting machine in which the leader has both horizontal and vertical movement.

Another object is to provide means for accurately positioning the leader when it is to be locked or held stationary.

Another object is to provide a leader locking mechanism which is absolutely free from lost motion while holding the leader, this mechanism being positive, direct and accurate in action but simple in construction and having the great advantage of ready applicability to a machine for cutting forms without any disassembling of the same.

In the drawings: Figure 1 is a partial elevation of a machine embodying my invention; Fig. 2 is a partial plan on line 2-2 of Fig. 1; Fig. 3 is a rear elevation of the parts shown in Fig. 2; and Fig. 4 is a detail of the leader locking member.

The machine comprises four vertical rods a which at their lower ends have secured to them the ways a' which support the slide a^2 .

To the slide a^2 is fastened in the usual manner a leader a^3 whose flanged opening a^4 co-operates with the knife form a^5 in guiding the knife a^6 throughout the circuit of its travel. The form a^5 acts as a presser foot to hold the work firmly on the table a^6 said form being secured to the lower end of a stem a^7 which is raised and lowered at the proper

times by means of a lever a^8 . The knife a^6 55 is on a knife-carrier a^9 rotatably mounted on stem a^7 that is provided with a roll a^{10} projecting into a slotted arm a^{11} which is swung around the axis of the rod a^7 by the usual devices which are operated by means of a 60 belt engaging the pulley a^{12} . At their upper ends the rods a are secured to a crosshead a^{13} that is fastened by means of a set screw to stem a^7 , said rods extending through, and guided by, bearings a^{14} on the frame of the 65 machine. The ways a' and the leader carried thereby are shifted toward and from the work by rods a' in unison with the knife-carrier and form a^5 .

When a tap is being cut from stock of the 70 same size as that for which the opening a^4 is designed then the leader and its slide are held stationary while the knife travels around its circuit. When, however, it is desired to cut a tap larger than that for which 75 the leader-opening a^4 is designed then as the knife travels in the direction of the arrow (Fig. 2) from the point marked x to the point marked y the leader and its slide are shifted toward the right and thereafter 80 while the knife is passing from the point marked z to the point marked w the leader and its slide are shifted back to the left to their first position again. Throughout the remainder of the operation the leader and 85 its slide must be held absolutely stationary to insure accurate cutting, especially while cutting around the point x .

When a tap is to be cut which is smaller than that for which the leader opening a^4 90 is designed then the leader and its slide are shifted toward the left as the knife passes from the point marked x to the point marked y and to the right as the knife passes from the point marked z to the point marked w . 95 It will thus be seen that the leader is designed for a middle or intermediate size and is used to cut either larger or smaller taps, a different form a^5 being used for each size that is cut.

The form a^5 is of the same size and shape as the tap that is cut and as will be seen from Fig. 2 there may be a sharp point x' around which the knife swings and abruptly changes its direction of movement and it is highly 105 desirable that the knife negotiate this part of the operation properly that the leader a^3 be held rigidly immovable since any slight

movement or play due for instance to lost motion between the parts of the mechanism which operates and controls the leader even though very slight would greatly deflect the 5 knife and cause defective cutting of the tap at that point sometimes producing a somewhat circular enlargement or other defect at the point.

It has been suggested to provide leader 10 locking and holding mechanism intended to meet these requirements but no such mechanism has been adapted for use with a leader that is shifted toward and from the work as well as laterally. Moreover in actual practice such mechanism was not effective and far from satisfactory so far as providing 15 efficient holding means was concerned because said mechanism comprised a multiplicity of inter-connected parts, the principle of 20 construction of which made it impossible to avoid more or less lost motion at connecting joints so that accurate and completely effective action of said mechanism was not had in actual practice and moreover such 25 lost motion resulted in rapid wear of the joints which in turn resulted in defective action of the mechanism.

In accordance with this invention the member which engages the slide to hold it 30 immovable during its periods of rest directly engages both its actuator, herein shown as a cam, and the leader carrying slide and in such position that wear does not affect the action of said member.

35 My invention further contemplates a direct and simple drive for the cam which actuates the locking member and the embodiment of the improvement in the form of an attachment which may be applied to 40 a machine of the type shown in said patent.

The gear b^{11} is the same as the gear c^2 of the patent referred to. As herein shown this gear b^{11} drives a gear 1 fixed to the upper end of a shaft 2 that is journaled in a 45 bracket 3 bolted to the frame. At its lower end shaft 2 carries a cam 4 that engages an arm 5 fast on a spindle 6 journaled on bracket 3. This spindle 6 has adjustably fastened to it by means of a set screw 7 a 50 depending arm 8 co-operating with a slotted lug 9 fixed to the leader carrying slide a^2 . As will be clear the arm 5, spindle 6 and arm 8 are rigidly secured together and constitute a single locking member for the 55 leader slide, the end of the arm 8 being wedge-shaped so that when arm 8 enters the slot of lug 9 as described later said wedge shaped end will act upon one side or the other of said slot to shift the slide to accurately position it as it is locked by said 60 arm 8. The cam 4 is timed so as to swing the arm 8 into engagement with the lug 9 when the knife reaches the point w ; to hold said arm in engagement with said lug while 65 the knife is traveling from the point w

around w' to the point x ; to swing said arm 7 away from said lug when the knife reaches the point x and to hold said arm out of engagement with the lug while the knife travels from x to w again. The lug 9 is 70 made of sufficient length to provide for vertical movement of the leader slide.

When the wedge-shaped arm 8 is thrust into engagement with the slot of lug 9 said engagement acts to accurately position the 75 curve a^2 of the leader relative to the point x' or, in other words, it acts to automatically and accurately position the leader as it locks it against movement, such positioning in machines for cutting forms being new 80 with me.

By means of the screw 7 the arm 8 may be adjusted to compensate for wear of cam 4, said arm 8 or said socket lug 9.

From the foregoing it will be observed that in effect only two parts intervene between the driving gear c^2 and the leader slide, one of said two parts being made up of gear 1, shaft 2 and cam 4 and the other of arm 5, spindle 6 and arm 8, so that the 90 driving gear b^{11} acts through the minimum number of relatively movable parts to control the leader slide instead of through a multiplicity of relatively movable parts and joints. 95

As will be clear the bracket 3 carries the entire leader slide locking and positioning mechanism so that said bracket with said mechanism may be applied to or removed from the fixed frame of the machine without disturbing any of the parts of the latter. In other words the locking mechanism herein shown is a self-contained, complete attachment that may be connected up with the ordinary mechanism of a machine of this 100 type merely by securing the bracket in position on the frame. 105

The means for actuating and adjusting the slide a^2 may include a shaft c' journaled in a bracket c^2 fixed to the frame of the machine, as well as arm c^{13} and link c^{14} and other elements fully disclosed in detail in U. S. Patent No. 961,907, dated June 21, 1910.

110 What I claim is:

1. A machine for cutting forms comprising a work table; a leader movable laterally and toward and from the work table; means for operating the leader; a knife controlled by said leader; means for operating the knife; a leader support; and means independent of said support to lock the leader during a part of the travel of the knife. 115

2. A machine for cutting forms comprising a leader; a support for said leader; means to operate the leader; a knife carrier guided by the leader; and means separate from the leader operating means and independent of said support to hold the leader immovable during a part of the travel of 120 125 130

the knife and to position the leader when it is to be held immovable.

3. A machine for cutting forms comprising a fixed frame; a work table; a leader carrier movable toward and from said work table; a leader slide; means for operating said slide; a movable locking member mounted on the fixed frame and adapted to directly engage the leader-carrying slide to lock it rigidly to said frame but with provision for movement of said slide toward and from the work table; and means to operate said locking member so as to cause it to engage the slide while the latter is held at rest by its operating means.

4. A machine for cutting forms comprising a knife; means for actuating the knife; a leader; means for operating the leader; a gear; means for operating said gear; a shaft to which said gear is fixed; a cam fast on said shaft; a bell crank lever actuated by said cam and coöperating directly with the leader slide, said cam operating the bell-crank lever so as to cause the latter to hold the leader slide immovable during a portion of the travel of the knife.

5. A machine for cutting forms comprising a leader carrier; a leader mounted on said carrier; a support for said carrier; means to operate the leader; and means separate from said leader operating means and independent of said support to first po-

sition said leader and then lock it immovable when said leader is held stationary by its operating means.

6. A machine for cutting forms comprising a knife; means for actuating the knife; a work table; a leader movable laterally and toward and from the work table; means for operating the leader; a gear; means for operating said gear; a shaft to which said gear is fixed; a cam fast on said shaft; and a bell crank lever actuated by said cam and coöperating directly with the leader slide, said cam operating the bell crank lever so as to cause the latter to hold the leader slide immovable during a portion of the travel of the knife.

7. A machine for cutting forms comprising a work table; a leader movable laterally toward and from the work table; a knife controlled by said leader; a shaft carrying a gear; means to rotate the shaft; leader operating means operated by said gear; a second gear distinct from said leader operating means but operated by said first gear; and means operated by said second gear to hold the leader immovable during a part of the travel of the knife.
